UNITED STATES PATENT OFFICE

2,475,660

LOCKING CENTER PIN FOR RAILWAY CARS

George E. Dath, Mokena, Ill., assignor to W. H. Miner, Inc., Chicago, Ill., a corporation of Delaware

Application May 5, 1945, Serial No. 592,143

3 Claims. (Cl. 105—200).

1.

This invention relates to improvements in locking center pin for railway cars.

The main object of the invention is to provide a bolster locking center pin for connecting the body and truck bolsters of a railway car comprising a pair of outer sections or members and a central filler element for holding the outer sections expanded, wherein the filler element is rotatable to bring the same into shouldered engagement with means on the lower end of one of the outer members of the pin to hold said element against removal in downward direction with respect to the outer sections, and the other outer member is provided with means for locking the filler element against rotation with respect to the first named outer member to maintain the means for holding the filler element against removal in operative position, the weight of said second named member being utilized to hold the same in locking position with respect to the filler element.

Other objects of the invention will more clearly appear from the description and claims herein-after following.

In the drawing forming a part of this specification, Figure 1 is a longitudinal, vertical sectional view taken through the mid-portions of the body and truck bolsters of a railway car, illustrating my improvements in connection therewith, the center pin being shown in elevation. Figure 2 is a top plan view of my improved locking center pin. Figure 3 is a view similar to Figure 1 with the body bolster omitted and the upper portion of the locking center pin broken away, showing the parts in a somewhat different position and illustrating the manner of applying the pin. Figure 4 is a transverse, horizontal sectional view of the lower end portion of the locking center pin, corresponding substantially to the line 4—4 of Figure 1. Figure 5 is a detailed perspective view of the lower end portion of the filler element of my improved locking center pin.

In said drawing, 10 indicates the body bolster of the car and 11, the truck bolster. These bolsters are of usual well-known design, the body bolster being provided with a center section 12 to accommodate the center pin, and the truck bolster being provided with an upstanding hollow boss or flange 13, projecting into the section 12 of the body bolster. The section 12 is of substantially tubular form having an inwardly projecting flange or rib 14 between the top and bottom ends thereof. The flange 14 defines an opening 15 adapted to accommodate the center pin. Above the flange 14, the section 12 forms

5 a pocket 16 adapted to accommodate the head at the upper end of the pin. The hollow boss 13 provides a circular opening 17 to accommodate the center pin. The opening 17 of the truck bolster and the opening 15 of the body bolster are in axial alignment. Below the opening 17, the truck bolster is provided with a pocket 18 having a bottom wall 19. The bottom wall 19 has an opening 20 therethrough axially aligned 10 with the openings 15 and 17, but of greater diameter than these openings. The pocket 18 serves the purpose of accommodating the head at the bottom end of the center pin. As shown in Figure 1, the pocket 18 is of greater size than the opening 17 of the boss 13, thereby providing a downwardly facing shoulder 21 adjacent said opening, which cooperates with a head at the bottom end of the center pin to restrict upward movement of the latter. The usual bearing plate or shim 22 is interposed between the body and truck bolsters around the upwardly projecting boss 13 of the truck bolster.

My improved locking center pin comprises broadly a pair of outer members or sections A and B and a central spreader or filler element C.

The two outer members or sections A and B are of similar design, except as hereinafter pointed out. Each outer member comprises a substantially semi-cylindrical shank 23 having heads 24 and 25 at the top and bottom ends thereof. The top head 24 is in the form of an eccentric, substantially semi-cylindrical, outstanding flange, and the bottom head 25 is in the form of a concentric, substantially semi-cylindrical flange. The members A and B are laterally spaced apart at the upper ends and have contact with each other on their inner sides at their lower ends. The member B is laterally inwardly enlarged at its lower end, as indicated at 26, to provide this contact. The zone of contact is on substantially flat, vertical faces, preferably of a vertical height at least as great as the thickness of the flange or head 25 of either of these members. Immediately above the zone of contact, the enlarged portion 26 of the member B inclines away from the member A in upward direction, as indicated at 27. The spaced arrangement of the upper end portions of the members A and B permits collapse of said upper end portions of the pin to make possible insertion and removal of said members.

The heads 24—24 at the upper end of the members A and B are made of such a size and contour that they will pass freely through the pin receiving openings 15 and 17 of the body and truck

bolsters when these members are inserted or removed in succession from underneath the truck bolster, with the filler member absent so that the upper portion of the center pin may be collapsed. The member A, which is the right hand member, as seen in Figure 1, has a depending lug 28 at the lower end thereof. The lug 28 comprises a transversely curved wall 29 and a laterally inwardly directed, horizontal shelf or ledge 30 at the lower end of said wall.

The member B, which is the left hand outer member, as viewed in Figure 1, is provided with a pair of depending locking projections or lugs 32-32 at the lower end thereof, which are diametrically opposed to the lug 28 of the member A. The lugs 32-32 are laterally spaced apart, thereby providing an opening or slot therebetween.

The filler element C comprises a cylindrical shank 33 and an eye member 34 at the lower end of the shank. A radially projecting finger or lug 35 extends from one side of the shank 33 above the eye member 34 in spaced relation thereto, and a vertically extending rib 36 projects laterally outwardly from the diametrically opposite side of said head. The rib 36 extends upwardly from the eye member 34 and has its upper end horizontally aligned with the upper side of the lug 35. The finger or lug 35 is of such a length that it overlaps the shelf 30 of the lug 28 when the element C is in the position shown in Figures 1, 2, and 4. The rib 36 is of such a width that it fits the opening between the lugs 32-32 and locks the element C against rotation when the lugs are engaged in straddling relation therewith.

The top end of the shank of the element C is preferably beveled off, as shown, to facilitate insertion of said element between the outer members A and B.

The inner sides of the members A and B are centrally vertically slotted or grooved, as indicated at 37. These slots or grooves are of concave cross section and, when the members A and B of the pin are in assembled position, form a central bore in which the shank 33 of the element C fits loosely and is rotatable.

As will be seen upon reference to Figure 1, when the pin comprising the outer members A and B and the filler element C interposed between said members is applied to the bolsters, the shank of the pin substantially fits the openings 15 and 17 of the body and truck bolsters with the heads 24-24 and 25-25 disposed respectively above the shoulder presented by the flange or rib 14 of the body bolster, and below the shoulder 21 of the truck bolster. The pin is thus held against removal in both downward and upward directions.

In applying the center pin to the bolsters, the member A is first inserted through the openings of the bolsters from underneath the truck bolster and displaced laterally outwardly to engage the heads 24 and 25 thereof with the shoulders of the bolsters. After this has been done, the member B is inserted from underneath the truck bolster, through the bolster openings alongside the member A. As will be evident, the inclined portion 27 of the member B provides the required clearance to permit inclining of this member to the proper extent to permit the head at the upper end to pass through the bolster opening. When the member B has been fully inserted, it will have been displaced laterally outwardly at its upper end by spreading apart of the lower end of the pin, to bring the head 24 thereof into shouldered engagement with the bolster 10, and, due to the

fact that the members A and B have their inner side faces adjacent the lower end of the pin contacting, the head 25 at the lower end of the member B will be forced to engage beneath the shoulder of the truck bolster. The member B is then pushed upwardly to the raised position shown in Figure 3 and held in that position by any suitable tool. The filler element C is next inserted between the members A and B from underneath the truck bolster to hold the members of the pin separated and in shouldered engagement with the body bolster. Before application of the element C, it is turned so that the lug or finger 35 and the diametrically opposite rib 36 thereof are in alignment with, and extend lengthwise of, the opening between the lug 28 and the lugs 32-32 at the lower ends of the members A and B. Inasmuch as the finger 35, when in this position, is free to pass the lug 28, the filler element may be shoved upwardly until the finger 35 is brought to a position above the level of the shelf or ledge 30 of the lug 28. With the finger 35 thus positioned above the level of the shelf 30 and the member B in raised position, the element C is given a quarter turn, thereby engaging the finger or lug 35 over the shelf or ledge 30 of the lug 28, and disposing the rib 36 in alignment with the opening between the lugs 32-32 of the member B. The member B is then permitted to drop downwardly to engage the lugs 32-32 over the rib 36, as shown in Figure 1.

The element C is thus securely held against rotation with respect to the members A and B, thereby preventing the finger 35 from moving out of engagement with the shelf or ledge 30, and possible accidental dropping out of the element C from between the members A and B.

In this connection it is pointed out that the outer members A and B of the pin are held against relative rotation or shifting with respect to each other about the vertical axis of the pin by the contact provided on their inner sides at the lower end thereof, thus at all times maintaining the lug 28 and the lugs 32-32 thereof in transverse alignment, thereby assuring proper accommodation of the rib 36 between the lugs 32-32 and finger 35 on the shelf 30 of the lug 28 of the member A.

In removing the center pin, the reverse procedure is followed. The member B is first pushed upwardly to lift the lugs 32-32 out of locking engagement with the rib 36 of the element C. The latter is then given a quarter turn to align the finger 35 thereof with the opening between the lugs of the members A and B. The element C is then withdrawn from between the members A and B by pulling the same downwardly, a hook or similar tool being used for this purpose, the eye 34 serving as a convenient means for anchoring the hook. After withdrawal of the filler element, the outer members are removed in succession, the member B being the first withdrawn.

I claim:

1. In car construction, the combination with body and truck bolsters having aligned center pin receiving openings; of a center pin insertable within said openings, said pin including a pair of outer members headed at opposite ends for shouldered engagement with said bolsters, and a central filler element interposed between said outer members for holding the same spaced apart, said filler element being rotatable and having a lateral projection at one side and a locking rib projecting from the opposite side at the lower end thereof, one of said outer members having a de-

pendent lug at its lower end provided with a horizontal ledge on which said projection is seated by rotation of said filler element to hold the latter against removal in downward direction, and the other outer member overhanging said rib of said element to restrict upward displacement of the latter and having a pair of laterally spaced, depending locking lugs engaged over and embracing said rib to hold said element against rotation with the projection thereof seated on said ledge.

2. In car construction, the combination with body and truck bolsters having aligned center pin receiving openings; of a center pin insertable from beneath said truck bolster, said pin comprising outer members headed at opposite ends, and a central filler element between said outer members, said filler element holding the pin expanded with the heads thereof in shouldered engagement with the bolsters, one of said outer members having a retaining ledge on the lower end thereof and the other of said outer members having a downwardly opening seat at its lower end, said filler element having a radially projecting locking finger at its lower end at one side thereof and an upstanding locking projection at the lower end at the other side thereof adapted to fit within said seat, said finger being engaged over said ledge to support said element against downward displacement, said outer member which has the seat overhanging said projection to restrict upward displacement of said element, and

said seat being engaged over said projection, in embracing relation to hold said element against rotation.

3. In a locking pin of the character described, the combination with a pair of elongated outer members having retaining flanges at the top and bottom ends; of a filler element between said outer members, said filler element being rotatable with respect to said members; a supporting ledge at the bottom end of one of said members; a pair of depending, laterally spaced locking lugs on the other of said members, said lugs being laterally spaced apart and opposed to said ledge; a radially projecting locking lug at one side of the lower end of said element adapted to rest on said ledge to support the element against downward displacement; and a radially projecting, upstanding rib extending from the opposite side of said element, said rib being engageable beneath said other member between said depending lugs to restrict upward displacement of said element and lock said element against rotation with respect to the outer members.
